7 Claims. (Cl. 23—200)

The present invention relates to the manufacture of magnetic recording material, more particularly it relates to the preparation of thermally stabilised magnetic acicular γ -Fe₂O₃ which is used in the recording layer.

As already known the usual magnetic recording materials consist of a ferromagnetic layer applied to a support. The ferromagnetic recording layer usually consists of a ferromagnetic powder, which has been homogenously divided in a binding agent.

The support is usually manufactured from cellulose triacetate, polyvinyl chloride or polyethylene terephthalate, the latter being either or not symmetrically or asymmetrically stretched.

The ferromagnetic recording layer is applied to a support starting from a dispersion of a ferromagnetic powder, most often γ -Fe₂O₃, into a solution of a binding agent, such as polyvinyl acetate, copolymers of vinylchloride and vinylacetate, cellulose esters, after-chlorinated polyvinyl chloride, copolymers of butadiene and acrylonitrile or self-hardening polymers.

The ferromagnetic dispersion is e.g. according to the knife coating process, roller coating process or the gravure offset process applied to the support. These coating techniques are described in "Verein Deutscher Ingenieure" 100, No. 13, p. 545-548.

The ferromagnetic layer is dried and sometimes calendered after coating.

Concerning the composition of the magnetic dispersion layer, as well as the usual supports and the manufacture of the magnetic recording material in general, may be referred to H. G. M. Spratt, "Magnetic Tape Recording," Heywood & Company Ltd., 1958, London, p. 113-139.

As known the recording properties of the recording layer are principally determined by the quality of the magnetic powder. In cases of high coercivity and low permeability an anisotropic magnetic powder is preferably used such as e.g. acicular γ -Fe₂O₃ (see Spratt, "Magnetic Tape Recording," p. 36). Consequently the preparation of acicular γ -Fe₂O₃ is aimed at.

From the U.S. patent specification 2,694,656 a process is known for the preparation of a ferromagnetic iron oxide powder which principally consists of acicular γ -Fe₂O₃ crystals with a length of 0.5 to 2 μ , with a cubic crystal lattice structure and having a coercivity of 200 to 500 Oersted and even higher.

In a first reaction (nuclei-forming process) a ferrous salt is precipitated by means of lye and oxidized to colloidal Fe₂O₃·H₂O by passing an air current through it.

In a second reaction (growing process) an amount of ferrous salt in aqueous medium is oxidized, together with the Fe₂O₃·H₂O nuclei of the first reaction, by means of aerial oxidation in the presence of iron at a temperature of 40 to 80° C. The nuclei are growing at the expense of the metallic iron to acicular Fe₂O₃·H₂O.

The formed Fe₂O₃·H₂O is then dehydrated by heating and then reduced to Fe₃O₄ from which by oxidation the magnetic acicular γ -Fe₂O₃ is formed whilst heating.

This process and especially the oxidation, whilst heating, of the Fe₃O₄ must be carried out very carefully in view of the obtaining of an iron oxide with good magnetic properties. During the oxidation one has to pay special attention, that no local overheating in the powder mass occurs, because hereby the magnetic γ -Fe₂O₃, which is

only thermally stable in a limited way, is converted into the paramagnetic hematite (α -Fe₂O₃).

It is obvious that in a process according to which magnetic acicular γ -Fe₂O₃ is prepared with a higher thermal stability against the conversion into the paramagnetic hematite, the oxidation step of the Fe₃O₄ faster occurs, with greater reproducibility and with a higher yield of γ -Fe₂O₃.

It is an object of this invention to prepare magnetic acicular γ -Fe₂O₃ with improved thermal stability.

It is a further object of this invention to manufacture a magnetic recording material containing a magnetic acicular γ -Fe₂O₃ which posses an increased thermal stability.

It has now been found that by the application of the classical method of preparation, magnetic acicular γ -Fe₂O₃ with much better thermal stability can be obtained if the nuclei forming and/or growing process takes place in the presence of a compound of a metal selected from the group consisting of molybdenum and tungsten, e.g., a molybdate, a tungstate or mixtures thereof.

The magnetic properties and the composition of the magnetic iron oxide prepared according to the classical method described in U.S. patent specification 2,694,656 and magnetic iron oxide prepared according to the present invention are compared with each other in the following table. The results under A, B and C relate to the classical method for the preparation of acicular γ -Fe₂O₃ and the results mentioned under D and E relate to a thermally stabilised acicular γ -Fe₂O₃.

The oxidation of the Fe₃O₄ was carried out at an average temperature of 300 to 400° C.

By number of cycles is meant, the number of times the same iron scrap is used in the growing process. In using repeatedly the same iron scrap, there appears to be a sharp decline in the thermal stability and an intense decrease of the remanence. As iron scrap mild steel was used.

	Number of Cycles	Coercivity in Oerstedt	Remanence In Gauss	Percent Mo	Percent α -Fe ₂ O ₃
A-----	1	322	2.040	0	1.2
B-----	4	290	1.700	0	1.2
C-----	20	240	1.500	0	2.3
D-----	1	348	2.080	1	0.5
E-----	20	290	2.060	1	0.8

From this table it results that it is quite difficult to obtain reproducible results according to the classical method and that the content of α -Fe₂O₃ is higher than obtained with thermally stabilised acicular γ -Fe₂O₃ obtained according to the present invention.

The content of the molybdenum and/or tungsten in the finally obtained γ -Fe₂O₃ amounts to 0.1 to 3%.

The increased thermal stability has consequently the advantage that the temperature for the oxidation of the Fe₃O₄ can be considerably increased without the formation in the formed ferri-oxide product of an important amount of paramagnetic Fe₂O₃. Owing to this increased temperature, the time for the oxidative process can be much shortened.

The increased thermal stability particularly appears from the differential thermal analysis curves (see drawing), made of the iron oxide mentioned under C and E in the above-mentioned table. As neutral body for the measurement barium carbonate has been used. The differential temperature curves show the difference in increase of the temperature of the sample and of the neutral body on the y-axis (ΔT) and the course of the time on the x-axis (t).

The temperature measured at the maximum of ΔT is indicated for each curve. It results therefrom that the

sample mentioned under E possesses an increased thermal stability. The explanation for this rapid increase of ΔT is to be referred to the fact, that during the conversion of magnetic $\gamma\text{-Fe}_2\text{O}_3$ in paramagnetic $\alpha\text{-Fe}_2\text{O}_3$ a number of calories is set free. This is done, as is stated in comparing of the curves C and E, much faster for the sample C, which means on a lower temperature than for sample E.

The following are preparations of thermally stabilized acicular $\gamma\text{-Fe}_2\text{O}_3$.

PREPARATION 1

1.2 kg. of crystalline ferrous sulfate are dissolved in 0.6 l. of water at room temperature and precipitated with a solution of 0.2 kg. of sodium hydroxide in 1 l. of water. The precipitated ferrous hydroxide is oxidized for 10 hr. by means of air blown through the mixture until the colloidal suspension shows a yellow color. This suspension containing nuclei of $\text{Fe}_2\text{O}_3\cdot\text{H}_2\text{O}$ together with one kg. of iron scrap and 2.5 g. of sodium molybdate are added to 10 l. of 5% aqueous ferrous sulfate. Through this reaction mixture, a finely divided air current of 80° C. is blown through the mixture for 12 hr. at a rate of 30 l. per minute. The formed $\text{Fe}_2\text{O}_3\cdot\text{H}_2\text{O}$ is washed and dried by atomization. Reduction by means of hydrogen between 350 and 450° C. for 30 minutes and subsequent oxidation by air between 300 and 400° C. yield a brown magnetic iron oxide having the following properties:

$H_c=328$ Oerstedt
 $B_r=2.040$ gauss
 Percent of $\alpha\text{-Fe}_2\text{O}_3=1.3$
 Percent of Mo=0.7

PREPARATION 2

$\text{Fe}_2\text{O}_3\cdot\text{H}_2\text{O}$ nuclei are prepared as described in Preparation 1, but by means of a first aqueous ferrous sulfate solution containing 3 g. of sodium tungstate. After the growing stage and the further processing as described in Preparation 1, a brown magnetic iron oxide is obtained having the following properties:

$H_c=341$ Oerstedt
 $B_r=2.060$ gauss
 Percent of $\alpha\text{-Fe}_2\text{O}_3=0.6$
 Percent of W=1.2

The following example illustrates the application of the acicular $\gamma\text{-Fe}_2\text{O}_3$ in a magnetic recording layer.

Example

The following composition is ground for 20 hrs. in a ball-mill:

$\gamma\text{-Fe}_2\text{O}_3$ of Preparation 1	kg	100	
1,2-dichloroethane	l	130	
Methanol	l	20	
Polyvinylbutyral (marketed by Wacker Chemie G.m.b.H., Munich, Germany, under the trade name Piloform BS (8% of free hydroxyl groups))		kg	4

To this mixture the following composition is added:

Piloform BS (trade name)	kg	17.2
Methanol	l	51
1,2-dichloroethane	l	71

After grinding for 48 hr. the obtained dispersion is filtered and applied onto a carrier of polyethylene terephthalate according to the roller coating system described in Verein Deutscher Ingenieure vol. 100, No. 13, p. 545-548.

I claim:

1. A method for preparing magnetic acicular $\gamma\text{-Fe}_2\text{O}_3$ with improved thermal stability from Fe_3O_4 comprising the steps of

(a) precipitating an iron (II) salt from an aqueous solution by means of a strong base, said precipitation

being carried out in the presence of a compound of a metal selected from the group consisting of molybdenum, and tungsten;

5 (b) oxidizing the acicular iron (II) hydroxide formed in step a to acicular $\text{Fe}_2\text{O}_3\cdot\text{H}_2\text{O}$ nuclei by blowing air through the suspension obtained in step (a);

(c) adding the suspension obtained step (b) to a solution of an iron (II) salt and treating this composition with air in the presence of iron metal, to enable the $\text{Fe}_2\text{O}_3\cdot\text{H}_2\text{O}$ nuclei to grow;

(d) separating and drying the acicular $\text{Fe}_2\text{O}_3\cdot\text{H}_2\text{O}$ particles obtained in step (c);

(e) dehydrating the acicular $\text{Fe}_2\text{O}_3\cdot\text{H}_2\text{O}$ whilst heating and reducing it between 300 and 450° C. to acicular Fe_3O_4 ; and

(f) oxidizing at 300-400° C. the Fe_3O_4 to magnetic acicular $\gamma\text{-Fe}_2\text{O}_3$ by means of a gas containing free oxygen.

2. A method for preparing magnetic acicular $\gamma\text{-Fe}_2\text{O}_3$ 20 with improved thermal stability from Fe_3O_4 comprising the steps of

(a) precipitating an iron (II) salt from an aqueous solution by means of a strong base;

(b) oxidizing the acicular iron (II) hydroxide formed in step (a) to acicular $\text{Fe}_2\text{O}_3\cdot\text{H}_2\text{O}$ nuclei by blowing air through the suspension obtained in step (a), said oxidation being carried out in the presence of a compound of a metal selected from the group consisting of molybdenum, and tungsten;

(c) adding the suspension obtained in step (b) to a solution of an iron (II) salt and treating this composition with air in the presence of iron metal, to enable the $\text{Fe}_2\text{O}_3\cdot\text{H}_2\text{O}$ nuclei to grow;

(d) separating and drying the acicular $\text{Fe}_2\text{O}_3\cdot\text{H}_2\text{O}$ particles obtained in step (c);

(e) dehydrating the acicular $\text{Fe}_2\text{O}_3\cdot\text{H}_2\text{O}$ whilst heating and reducing it between 300 and 450° C. to acicular Fe_3O_4 ; and

(f) oxidizing at 300-400° C. the Fe_3O_4 to magnetic acicular $\gamma\text{-Fe}_2\text{O}_3$ by means of a gas containing free oxygen.

3. A method for preparing magnetic acicular $\gamma\text{-Fe}_2\text{O}_3$ 35 with improved thermal stability from Fe_3O_4 comprising the steps of

(a) precipitating an iron (II) salt from an aqueous solution by means of a strong base;

(b) oxidizing the acicular iron (II) hydroxide formed in step (a) to acicular $\text{Fe}_2\text{O}_3\cdot\text{H}_2\text{O}$ nuclei by blowing air through the suspension obtained in step (a);

(c) adding the suspension obtained in step (b) to a solution of an iron (II) salt and treating this composition with air in the presence of iron metal and a compound of a metal selected from the group consisting of molybdenum and tungsten, to enable the $\text{Fe}_2\text{O}_3\cdot\text{H}_2\text{O}$ nuclei to grow;

(d) separating and drying the acicular $\text{Fe}_2\text{O}_3\cdot\text{H}_2\text{O}$ particles obtained in step (c);

(e) dehydrating the acicular $\text{Fe}_2\text{O}_3\cdot\text{H}_2\text{O}$ whilst heating and reducing it between 300 and 450° C. to acicular Fe_3O_4 ; and

(f) oxidizing at 300-400° C. the Fe_3O_4 to magnetic acicular $\gamma\text{-Fe}_2\text{O}_3$ by means of a gas containing free oxygen.

4. Method for preparing magnetic acicular $\gamma\text{-Fe}_2\text{O}_3$ 40 according to claim 1, wherein a molybdenum compound is added to such an amount that the magnetic acicular $\gamma\text{-Fe}_2\text{O}_3$ contains from 0.1 to 3% by weight of molybdenum.

5. Method for preparing magnetic acicular $\gamma\text{-Fe}_2\text{O}_3$ 45 according to claim 2, wherein a molybdenum compound is added to such an amount that the magnetic acicular $\gamma\text{-Fe}_2\text{O}_3$ contains from 0.1 to 3% by weight of molybdenum.

6. Method for preparing magnetic acicular $\gamma\text{-Fe}_2\text{O}_3$ 50 according to claim 3, wherein a molybdenum compound is added to such an amount that the magnetic acicular $\gamma\text{-Fe}_2\text{O}_3$ contains from 0.1 to 3% by weight of molybdenum.

7. Method for preparing magnetic acicular γ - Fe_2O_3 according to claim 3, wherein a molybdate is added.
